SILK THROWING AND QUILL OR COP
FORMING APPARATUS

Joseph P. McHugh, Scranton, Pa., assignor, by
mesne assignments, to Industrial Machine Cor-
poration, a corporation of Delaware

Original application June 6, 1933, Serial No.
674,568. Divided and this application May 20,
1936, Serial No. 80,895

29 Claims. (Cl. 117—28)

This application is a division of my copending application Serial No. 674,568, filed June 6, 1933.

This invention relates to an improved apparatus for throwing silk or rayon and for forming cops or quills and is especially well adapted for making silk and rayon crepe cops or quills. While machines have heretofore been devised for doubling and twisting yarn, such as exemplified by the patent to Allen No. 775,550, none of the prior art methods or machines have been adapted for use in quilling silk and rayon, more especially silk crepe.

It is the purpose of the present invention to provide an economical apparatus for both throwing silk and forming quills and to provide for forming quills of crepe silk ready for the shuttle which will not snarl in weaving.

It is conventional practice in throwing silk and rayon crepe and forming rayon and silk crepe cops or quills to employ five separate operations which render the same laborious and expensive.

By the instant invention, both the silk throwing and cop or quill forming may be directly accomplished in one uninterrupted operation in a single machine.

It is also an object of this invention to provide, in a concurrent silk throwing and quill or cop forming machine, suitable apparatus for effecting efficient control of the thread supply to prevent overrunning of the supply holders.

Still another object of this invention is to provide, in a concurrent silk throwing and quill or cop forming machine, suitable apparatus for effecting complete control of the rotation of the various thread supplies and spun yarn holders, as a result of slack in or breakage of any of the individual thread strands.

A still further object of the invention is to provide a form of drive for the various spindles, thread feeding means, and traverse mechanism of a multi-unit spinning machine which will assure complete synchronization of the speed of operation of all of these various instrumentalities during all periods of operation of the machine.

It is a further object to provide a novel mounting for the skein swifts or reels and to provide other specific improvements in the doubling and winding mechanism.

Other and more detailed objects and advantages will become apparent as the description proceeds.

The invention will be described by reference to the accompanying drawings wherein:

Figure 1 is a view in side elevation of a complete quill or cop forming machine unit;

Figure 2 is a front elevation of the machine shown in Figure 1;

Figure 3 is a detailed view showing a part of the traverse drive mechanism;

Figure 4 is a view taken at a right angle to Figure 3 showing the traverse control cams;

Figure 5 is an enlarged detailed view of the roller mechanism and quill spindle release rod mounting;

Figure 6 is a top plan view of the roller mechanism as shown in Figure 5;

Figure 7 is a fragmentary detailed view taken on line 7—7 of Figure 5;

Figure 8 is a detail of the latching mechanism taken on line 8—8 of Figure 5;

Figure 9 is a detailed view showing the quill mounting and drive;

Figure 10 is an enlarged detail view showing the central skein carrying drum and one skein carrying arm; and

Figure 11 is a fragmentary detailed view taken at a right angle to Figure 10.

Referring to Figure 1, there is a base frame 1 on which the entire mechanism is assembled. A motor 2 is centrally carried on the frame 1 and drives a power belt 3. The frame 1 is designed to carry rows of complementary units at each side thereof. These are, however, constructed in duplication. Therefore, only a single left-hand unit is shown and will be described. The belt 3 drives pulleys 4 and 4'. The shaft 5 extends down from pulley 4' and carries a worm 6 at the lower end thereof which meshes with a worm gear 7 mounted on a shaft 8 carrying a sprocket 9. A sprocket chain 10 is trained around the drive sprocket 9. The sprocket chain 10 drives the traverse mechanism, designated broadly A, and also the roller mechanism designated broadly B. Chain 10 passes about sprockets 11, 12, and 13. Sprocket 11 in turn drives bevel gears 14 and 15, transmitting power to shaft 16 suitably carried by the frame 1. Power is transmitted through shaft 16 for controlling the movement of the traverse mechanism A, to be later described in detail.

The sprocket 12 drives bevel gears 17 and 18 transmitting power to shaft 19 for driving the roller mechanism B. The quill spindle 20 carries an enlarged hub 21 normally in driving contact with the belt 3. The spindle 20 is so mounted at its base that it can be swung to and from contact with the drive belt 3 so that the spindle of any unit may be removed from driving engagement with the belt without stopping the machine or disturbing other units.

45

50

55

Coming now to a description of the mountings for the swifts or reels for the skeins, there is rigidly secured to the upper end of the frame 1 a main supporting arm 22. The arm 22 carries at its free end a central hub 23. The hub 23 in turn carries four arms 24, each carrying at its free end a swift or reel 25. Each reel 25 is constructed to receive a skein. The central hub 23 is rotatably carried by the arm 22 so that any swift or reel 25 may be brought within reach of the operator for tying broken strands or replacing skeins. A locking mechanism for holding the hub 23 in any given position of adjustment with respect to the arm 22 is provided and includes the latch detent 26 extending through arm 22 and adapted to be selectively projected into the holes 27 (see Figure 10) of the hub 23.

The manner of taking off the strands from the individual skeins is such that the hub 23 can be moved to and held in any position of adjustment without interfering with the operation of the machine. The end of the strand from each skein is threaded through a porcelain eye 28 carried by hub 23, and each strand then passes transversely of the hub 23 to the single porcelain condensing guide 29 carried by the arm 22' of the next adjacent unit. From the guide 29 the condensed strand, designated 30, is passed down to the roller mechanism B (see Figure 2).

Due to the extreme difficulty of providing perfectly balanced reels or swifts and, further, to the uneven moisture content at different portions of the skeins mounted thereon, it becomes necessary to provide an individual braking mechanism for each swift or reel to insure a uniform tension of the separate strands taken off from the several skeins.

The braking mechanism for each swift or reel is identical and only one will be described. Each swift 25 is provided with a braking surface 31 (see Figure 10). A rubber brake shoe 32 is adapted to bear against the surface 31. The shoe 32 is carried by a wire rod 33 pivotally supported on an insulating bracket 34 carried by the swift supporting arm 24. A coil spring 35 is connected to the rod 33 and tensioned to normally urge the shoe 32 against the surface 31. The opposite end of the rod 33 (see Figure 11) is bent outwardly and passed through a guide loop 36 and terminates in a right angularly bent end 37. Now the porcelain eye 28 is carried by a wire rod 38 pivotally mounted in an insulated bracket 39 carried by the central hub 23. A spring 40 normally urges the rod 38 and porcelain eye 28 inwardly toward the hub 23.

The bent end 37 of brake rod 33 extends just outside the rod 38 carrying the eye 28. The arrangement is such that when a strand is being pulled through the eye 28 under normal tension, the eye 28 is pulled outwardly against the tension of spring 40 and in turn pulls the lower end of rod 33 out by virtue of its bent end 37. This causes rod 33 to have pivotal movement on the bracket 34 against the tension of spring 35 and thus release the brake shoe 32.

When the swift or reel rotates too fast, due to any unbalanced condition, it tends to cause a slack in the strand and destroys the normal tension. When this happens, the spring 35 immediately applies brake shoe 32 to the swift and slows it down until normal tension of the strand is restored.

At this point it is well to note that the arm 38 carrying eye 28 is also adapted, when a strand breaks, to be forced by spring 40 against contact

member 41 to close a circuit for controlling a stop mechanism to be hereinafter described in more detail.

Coming now to the roller mechanism B, a main supporting bracket arm 42 is secured to the upper end of the base frame 1 and supports the entire roller mechanism. The shaft 19 passes longitudinally of the arm 42 to drive the roller 43 through bevel gears 44 and 45 (see Figures 5 and 6). The supporting arm 42 has fixed thereto a right angularly disposed bar 46. At the lower end of bar 46 there is affixed an extension arm 47 in parallelism with the arm 42. Pivotally mounted on the free end of arm 47 is a swinging bar 48. The swinging bar 48 is provided with a bearing 49 for the shaft 50 carrying the roller 43 and the bevel gear 45. The swinging bar 48 is biased away from the bevel gear 44 on shaft 19 by a coil spring 51 surrounding the pivot 52 upon which the bar 48 is journaled.

The swinging bar 48 is normally held in position with the gear 45 in mesh with bevel gear 44 against the tension of spring 51 by a latch bar 53. The latch bar 53 is provided with a slot 54 through which a bolt 55 extends for attaching the latch bar 53 to the swinging bar 48.

Mounted on the upper end of bar 46 (see Figure 8) is a bracket 56, which carries a casting 57 pivoted at 58 and adapted in normal position to cooperate with a projection 59 on the end of latch bar 53 to hold the swinging bar 48 in position with gears 44 and 45 in mesh. The casting 57 also carries an electromagnet 60 and a pivoted armature 61. The armature 61 pivoted at 62 carries a trigger finger 63 adapted, when the magnet 60 is energized, to engage a projection 64 carried by the gear 44 on shaft 19.

The arrangement is such that, when the electromagnet 60 is energized through the closing of a circuit due to the breaking of a strand, the armature 61 is attracted and causes the trigger 63 to move into the path of a projection 64 on gear 44.

The projection 64 moves the trigger 63 and rocks the casting 57 about the axis 58 to release the latch bar 53. Release of latch bar 53 allows spring 51 to swing the arm 48 to cause disengagement of bevel gears 44 and 45 and allow roller 43 to stop.

Passing now to the means for disconnecting the quill carrying spindle 20 from the driving belt 3, it will be noted that the latch bar 53 is provided at its outer end with an aperture 65 through which extends a spindle releasing rod 66. The rod 66 is pivotally mounted at its lower end on a pivot 67, about which it is moved by the latch arm 53 when swinging arm 48 is released and moved by the spring 51.

As shown in Figure 2, the spindle releasing rod 66 extends behind a finger 68 carried by the mounting 69 for spindle 20. It will be observed that the mounting 69 is journaled upon a vertical pivot 70 which is eccentric to the axis of spindle 20, the vertical pivot 70 being supported by a fixed bracket 71 carried by the frame 1. There is also carried by the bracket 71 a fixed brake shoe 72 (see Figures 2 and 9).

The action is as follows: The mounting 69 carrying the spindle 20 is normally urged toward the belt 3 by a coil spring 73 (see Figure 9) to insure driving engagement between belt 3 and spindle hub 21. Now, when magnet 60 (Figure 5) causes the release of latch bar 53, the latter, due to the action of spring 51, forces spindle releasing rod 66 outwardly against the finger 68 to

swing the spindle mounting 69 about the eccentric pivot 70 and move the spindle hub 21 from engagement with belt 3 and into engagement with fixed brake shoe 72 to stop the spindle.

5 Before leaving the spindle releasing rod 66, it will be further observed that when this rod is moved to release spindle hub 21 from driving engagement with belt 3, it also opens, through the medium of rod 74, contacts 75 in series with magnet 60 to de-energize the same. The swinging arm 48 and spindle releasing rod 66 remain in their released position, until manually restored by re-engagement of the latch 59 on bar 53 with the pivoted casting 57, to maintain the 10 roller 43 and the spindle 20 inoperative.

15 Returning to the roller 43, the composite strand 30 coming from the porcelain guide eye 29 is drawn through a porcelain eye 76 supported by the latch bar 53 in a position directly above the left-hand end of roller 43, as viewed from the front. The bolt 55 carries a porcelain guide 77 immediately above the roller 43. The roller 43, which is mounted to rotate with shaft 50 and bevel gear 45, is provided on its circumference 20 with three flat-bottomed grooves or channels 78, 79, and 80 separated by square shouldered flanges 81.

25 The thread 30 leaves the eye 76, enters the groove 78 adjacent the left side thereof, is carried once around roller 43 in groove 78, thence passes over porcelain guide 77 into the groove 79 and once again around the roller 43 in groove 79, and thence passes again over porcelain guide 77 to groove 80 to porcelain eye 82 and on to 30 the traverse mechanism hereinafter described. The thread is caused to roll axially of the roller 43 in the grooves thereon, whereby the thread delivered to the traverse mechanism is partially twisted. The flat-bottomed grooves 78, 79, and 35 80, together with the square shouldered flanges 81, are particularly advantageous in giving a tightly twisted thread and preventing snarling and entangling of the thread upon the roller.

40 The improved traverse operating and control mechanism by which applicant's novel method of quill forming is accomplished will now be described. Returning to the driven shaft 16, a heart-shaped cam 83 is carried thereby, which oscillates an arm 84 loosely journaled upon a 45 rocker shaft 85 extending parallel to shaft 16.

45 The arm 84 carries a cam follower roller 86 which rides on cam 83 to cause oscillation of arm 84. The arm 84 also carries a shaft 87 journaled therein, on one end of which is fixed a half-heart 50 cam 88 and on the other end of which is carried a worm gear 89. The worm gear 89 and half-heart cam 88 are driven from shaft 16 by means of sprocket 90 on shaft 16, chain 91, and the sprocket 92 mounted on rotating sleeve 93 loosely journaled upon shaft 85. The sleeve 93 carries 55 at its opposite end a worm gear 94 which drives a worm gear 95 upon a shaft 96 extending at right angles to shaft 85 and journaled in a bearing 97 carried by rocker arm 84. The shaft 96 60 carries at its opposite end a worm 98 which drives gear 89 and half-heart cam 88.

65 The shaft 85 has affixed thereto a rocker arm 99 which carries at its free end a cam follower roller 100 riding upon the half-heart cam 88. Shaft 85 carries at its outer end a bell-crank lever 101 (see Figure 2), the horizontal arm of which carries a roller 102 at its free end. The roller 102 engages a thrust plate 103 on the lower end of the traverse reciprocating rod 104 70 mounted in a guide bearing 105, supported on 75

frame 1 and carrying horizontal ring supporting rods 106 at its upper end. The rods 106 are common to a plurality of units and carry the ring 107. The vertical arm of bell-crank 101 is pivotally connected to a rod 108 which operates bell-cranks similar to 101, which are individual to other units and cooperate to actuate ring-supporting rods 106. The ring 107 receives and guides the thread 30 as it is wound to form a cop or quill on the spindle 20.

10 The operation of the traverse is as follows: The heart cam 83 directly driven by shaft 16 rotates at a relatively rapid speed and produces, through arms 84, 99, and 101, traverse movement of uniform amplitude. The amplitude of the uniform traverse is controlled by the size of cam 83 and is intentionally always less than the desired length of quill or cop to be formed. The half-heart cam 88 controls the traverse gain on the quill. Cam 88 moves much slower than cam 83. 15 A ratio of 15 to 1 is found satisfactory, although this may be varied if desired. On each rotation of cam 83 there is but a small movement of cam 88 which, translated to the traverse, causes it to gain on each rotation of cam 83 proportioned to 20 the movement and pitch of the cam 88.

25 The cam 88 is so constructed that the cam follower 100 rides, during seven-eighths of each revolution thereof, on the curved face of the cam and returns to the point of beginning in but one-eighth of a revolution of cam 88. It will thus be observed that after the total gain provided by the curved surface of cam 83 has been effected, there is a quick return to the point of beginning. Due to the form of cam follower 100, the return is 30 effected in much less than one-eighth of a revolution of cam 88. Translated to the quill or cop which the winding commences at the bottom, the upward traverse is uniform. The downward 35 traverse is also uniform but is always shorter than the upward traverse. When the topmost traverse is reached, the thread is rapidly returned to the bottom of the quill and the cycle repeated.

40 The cop or quill is built up from the bottom by successive layers of thread, each layer comprising 45 a plurality of overlapping traverses. This results in the formation of a cop or quill having a very effective interlocking wind and one which will unwind in the shuttle on weaving without snarling. This feature of the invention is of great 50 value, and I am not to be limited to the precise form of mechanical movement disclosed, by which this advantageous result is obtained, since other mechanism than that shown may be employed.

55 No electrical diagram of the circuit for the electromagnet 60 of the stop mechanism is shown, it being obvious that this circuit is closed upon the breaking of any one of the strands coming from the skeins on reels 25 through the action of the rod 38 carrying the porcelain eye 28, as heretofore described, and that the circuit is broken by the spindle release rod 66 when the stop mechanism has been actuated.

60 In accordance with the present invention, it is possible to throw silk and form crepe silk or rayon 65 cops or quills in one uninterrupted operation with but one twisting and winding operation. This has never, to my knowledge, been heretofore accomplished. Crepe silk or rayon requires around sixty-five twists per linear inch, and no machine 70 has heretofore been devised for both throwing the silk and giving a cop or quill of thread of this character directly ready for the shuttle of the loom. According to this invention, the quill spindle is driven at a very high speed approx- 75

imating 15,000 R. P. M. With this permissible speed and the method of twisting and cop forming employed, I am able to turn out crepe silk or rayon quills or cops in one operation, taking the 5 rovings from the skeins and producing finished cops.

The foregoing description is illustrative only, the invention being limited and restricted only by the scope of the appended claims.

10 Having thus described my invention, what I claim is:

1. In a throwing and winding machine, a support, a frame rotatably mounted on said support, a plunger carried by said support for positioning 15 said frame, and a plurality of swifts rotatably mounted on said frame and arranged to feed yarn from more than one swift in all positions of the frame.

2. In a throwing and winding machine, a support, a frame comprising radially extending arms 20 pivotally mounted on said support, swifts pivotally supported upon said arms, braking means for said swifts, and means controlled by the yarns from said swifts for controlling said braking 25 means.

3. In a throwing and winding machine, a support, a frame pivotally mounted on said support, swifts pivotally mounted on said frame, a holder upon which yarn from the swifts is wound, braking 30 means for said swifts and holder, and means governed by the yarns from said swifts for controlling said braking means.

4. In a throwing and winding machine, a support, a swift frame pivotally mounted on said support, swifts rotatably mounted on said frame, a holder upon which yarn from said swifts is wound, braking means for said holder, and yarn 35 guides for said swifts carried by said frame and controlling said holder braking means.

40 5. In a throwing and winding machine, a support, a swift rotatably mounted on said support, braking means for said swift, yielding means continuously operating said braking means, and a yarn guide for said swift mounted on said support for movement independently of said brake 45 for controlling the operation of said yielding means.

6. In a throwing and winding machine, a support, a swift rotatably mounted on said support, braking means continuously opposing the rotation 50 of said swift, and means for increasing the resistance to the rotation of said swift upon the interruption of the yarn from said swift.

7. In a throwing and winding machine, a swift support, a swift rotatably mounted on said support, continuously operating braking means for said swift, a holder upon which the yarn from said swift is wound, electrically controlled braking means for said holder, and a guide arm for 60 the yarn from said swift controlling said swift braking means as a result of slack in the yarn and the circuit of said holder braking means as a result of breakage in the yarn.

8. In a throwing and winding machine, a swift support, a swift rotatably mounted on said support, means continuously opposing the rotation of said swift, a holder upon which the yarn from said swift is wound, electrically controlled means for braking said holder, and means operative 70 upon the interruption of the yarn from said swift to control said holder braking means and increase the resistance by said means to the rotation of said swift.

9. In a down ring-spinning machine, a multiple swift mechanism including a rotatable cen-

tral hub, a plurality of radially extending swift supporting arms carried by said hub, and a thread guide individual to each swift carried by said hub concentric with the axis thereof, whereby rotation of the hub does not interfere with removal of threads from the several skeins mounted on said swifts.

10. In a down ring-spinning machine, a multiple swift mechanism including a rotatable central hub, a plurality of radially extending swift supporting arms carried by said hub, a thread guide individual to each swift carried by said hub concentric with the axis thereof, whereby rotation of the hub does not interfere with removal of threads from the several skeins 15 mounted on said swifts, and means for holding said hub in a plurality of positions of rotary adjustment to facilitate access to the several swifts for tying broken threads or replacing exhausted skeins.

11. In a down ring-spinning machine, a multiple swift mechanism including a rotatable central hub, a plurality of radially extending swift supporting arms carried by said hub, a thread guide individual to each swift carried by said hub concentric with the axis thereof, whereby rotation of the hub does not interfere with removal of threads from the several skeins mounted on said swifts, and braking means for each 25 swift responsive to variations in the tension of the thread removed therefrom.

12. In a down ring-spinning machine, a multiple swift mechanism including a rotatable central hub, a plurality of radially extending swift supporting arms carried by said hub, a thread 35 guide individual to each swift carried by said hub concentric with the axis thereof, whereby rotation of the hub does not interfere with removal of threads from the several skeins mounted on said swifts, braking means for each swift responsive to variations in the tension of the thread removed therefrom, and means connecting said guides with said braking means so arranged that the normal tension of the threads passing through the guides maintains the braking 40 means inoperative.

13. In a throwing and winding machine, a support, a frame rotatably mounted on said support, means for holding the frame in different positions relative to the support, a plurality of swifts rotatably mounted on said frame, and means constructed and arranged to simultaneously feed yarn from all of the swifts in all positions of the frame.

14. In a throwing and winding machine, a support, a frame rotatably mounted on said support, means for holding the frame in different positions relative to the support, a plurality of swifts rotatably mounted on said frame, means constructed and arranged to simultaneously feed 55 yarn from all of the swifts in all positions of the frame, braking means for the swifts, and means controlled by the yarns from the swifts for controlling said braking means.

15. In a throwing and winding machine, a swift support, a swift rotatably mounted on said support, braking means for said swift, a holder upon which the yarn from said swift is wound, braking means for said holder, guiding means for the yarn from said swift affected by slack in and breakage of said yarn, means operated by the guiding means when slack occurs for controlling only the braking means for the swift, and means operated by the guiding means 70 75

- when breakage occurs for controlling the braking means for both the swift and the holder.
16. In a throwing and winding machine, a swift support, a swift rotatably mounted on said support, braking means for said swift, a holder upon which the yarn from said swift is wound, braking means for said holder, and guiding means for the yarn from said swift for controlling operation of the swift braking means when slack occurs in the yarn and for controlling operation of both the swift and holder braking means when a breakage of the yarn occurs.
17. In a throwing and winding machine, a swift support, a swift rotatably mounted on said support, braking means for said swift, a holder upon which the yarn from said swift is wound, braking means for said holder, yarn feeding means operable at a point between the swift and the holder, guiding means for the yarn from said swift affected by slack in and breakage of said yarn, means operated by the guiding means when slack occurs for controlling only the braking means for the swift, and means operated by the guiding means when breakage occurs for controlling the braking means for both the swift and the holder.
18. In a throwing and winding machine, a swift support, a swift rotatably mounted on said support, braking means for said swift, a holder upon which the yarn from said swift is wound, braking means for said holder, yarn feeding means operable at a point between the swift and the holder, and guiding means for the yarn from said swift for controlling operation of the swift braking means when slack occurs in the yarn and for controlling operation of both the swift and the holder braking means when breakage of the yarn occurs.
19. In a throwing and winding machine, a swift support, a swift rotatably mounted on said support, braking means for said swift, a holder upon which the yarn from said swift is wound, electric braking means for said holder, guiding means for the yarn from said swift affected by slack in and breakage of said yarn, means operated by the guiding means when slack occurs for controlling only the braking means for the swift, and means operated by the guiding means when breakage occurs for controlling the circuit for the electric braking means for the holder and for controlling the braking means for the swift.
20. In a throwing and winding machine, a swift support, a swift rotatably mounted on said support, braking means for said swift, a holder upon which the yarn from said swift is wound, electric braking means for said holder, and guiding means for the yarn from said swift for controlling operation of the swift braking means when slack occurs in the yarn and for controlling operation of the braking means for the swift and the circuit for the electric braking means for the holder when a breakage of the yarn occurs.
21. In a throwing and winding machine, a swift support, a swift rotatably mounted on said support, braking means for said swift, a holder upon which the yarn from said swift is wound, electric braking means for said holder, yarn feeding means operable at a point between the swift and the holder, guiding means for the yarn from said swift affected by slack in and breakage of the yarn, means operated by the guiding means when slack occurs for controlling only the braking means for the swift, and means operated by the guiding means when breakage occurs for controlling the braking means for the swift and the holder upon which the yarn from said swift is wound, electric braking means for said holder, and guiding means for the yarn from said swift for controlling operation of the swift braking means when slack occurs in the yarn and for controlling operation of both the swift and holder braking means when a breakage of the yarn occurs.
22. In a throwing and winding machine, a swift support, a swift rotatably mounted on said support, braking means for said swift, a holder upon which the yarn from said swift is wound, electric braking means for said holder, yarn feeding means operable at a point between the swift and the holder, and guiding means for the yarn from said swift for controlling operation of the swift braking means when slack occurs in the yarn and for controlling operation of the swift braking means and the circuit for the holder braking means when a breakage of the yarn occurs.
23. In a down ring spinning machine, a multiple swift mechanism including a rotatable central hub, a plurality of radially extending swift supporting arms carried by said hub, a thread guide individual to each swift carried by said hub concentric with the axis thereof, whereby rotation of the hub does not interfere with removal of thread from the several skeins mounted on said swifts, and condensing means for the thread leaving said guides positioned in axial alignment with the central hub.
24. In a down ring spinning machine, a multiple swift mechanism including a rotatable central hub, a plurality of radially extending swift supporting arms carried by said hub, a thread guide individual to each swift carried by said hub concentric with the axis thereof, whereby rotation of the hub does not interfere with removal of thread from the several skeins mounted on said swifts, condensing means for the thread leaving said guides positioned in axial alignment with the central hub, and means for feeding the doubled threads away from the condensing means.
25. In a down ring spinning machine, a multiple swift mechanism including a rotatable central hub, a plurality of radially extending swift supporting arms carried by said hub, a thread guide individual to each swift carried by said hub concentric with the axis thereof, whereby rotation of the hub does not interfere with removal of thread from the several skeins mounted on said swifts, condensing means for the thread leaving said guides positioned in axial alignment with the central hub, means for feeding the doubled threads away from the condensing means, and a holder on which the threads from the feeding means are wound.
26. In a throwing and winding machine, a revoluble support, a plurality of thread supply holders mounted on said support, means for guiding threads from all of said supply holders to and doubling the same at a point in alignment with the axis of said support, and a holder on which the doubled threads are wound.
27. In a throwing and winding machine, a revoluble support, means for holding said support in different positions of rotation, a plurality of thread supply holders mounted on said support, means for guiding threads from all of said supply holders to and doubling the same at a point in alignment with the axis of said support, and a holder on which the doubled threads are wound.
28. In a throwing and winding machine, a revoluble support, a plurality of thread supply holders mounted on said support, means for guiding threads from all of said supply holders to and doubling the same at a point in alignment with the axis of said support, a holder on which the doubled threads are wound, braking means for the last mentioned holder, and means for effect-

ing operation of said breaking means to effect stoppage of its holder upon breakage of any one of the threads from said supply holders.

29. In a throwing and winding machine, means for supporting a plurality of revoluble thread supply holders in parallelism and grouped about

a common center, means for guiding threads from all of said supply holders to and doubling the same at a point coaxial with said common center, a holder, and means for twisting and winding the doubled threads on said holder.
